(57) **CLAIM**

The ornamental design for a ball thrower, as shown and described.

DESCRIPTION

FIG. 1 is a top view of a ball thrower of my new design; FIG. 2 is a bottom view of the ball thrower thereof; FIG. 3 is a right-side view of the ball thrower; FIG. 4 is a right-side view of the ball thrower being shown in an alternate configuration; FIG. 5 is a left-side view of the ball thrower of FIG. 3; FIG. 6 is a left-side view of the ball thrower of FIG. 4; FIG. 7 is a front view of the ball thrower of FIG. 3; FIG. 8 is a front view of the ball thrower of FIG. 4; FIG. 9 is a rear view of the ball thrower of FIG. 3; FIG. 10 is a rear view of the ball thrower of FIG. 4; FIG. 11 is a perspective view of the ball thrower of FIG. 3; and, FIG. 12 is a perspective view of the ball thrower of FIG. 4. Portions of the claimed design are shown separated and bound by a bracket to indicate indeterminate length.
